Frederick A. Poole, Barrington, Ill., assignor to
Production Instrument Company, Chicago, Ill.,
a corporation of Illinois

Application December 10, 1938, Serial No. 81,707

Term of patent 14 years

To all whom it may concern:

Be it known that I, Frederick A. Poole, a citizen
of the United States, residing in the village of
Barrington and State of Illinois, have invented
a new, original, and ornamental Design for a
Counting Device, of which the following is a
specification, reference being had to the accom-
panying drawing forming part thereof.

Fig. 1 is a view in perspective of a counting
device showing my new design;

Fig. 2 is an end elevational view.

I claim:

The ornamental design for a counting device,
substantially as shown.

FREDERICK A. POOLE.
